UNITED STATES PATENT OFFICE.

GUY ATHERTON RIGHTER, OF DECATUR, ILLINOIS.

DESIGN FOR A CARPET-STRETCHER.

SPECIFICATION forming part of Design No. 30,481, dated April 4, 1899.

Application filed March 10, 1899. Serial No. 708,606. Term of patent 7 years.

To all whom it may concern:

Be it known that I, GUY ATHERTON RIGHTER, a citizen of the United States, residing at Decatur, county of Macon, State of Illinois, have **5** invented and produced a certain new and useful Design for Carpet-Stretchers, of which the following is a description.

In the accompanying drawings, which form a part of this application, Figure 1 is a **10** perspective view showing my design. Fig. 2 is a bottom plan view.

The body part or frame A of my design is parallelogrammatic in outline, having a plane upper surface *a* and having an under surface **15** B, marked by a plurality of lines forming ridges *b* and grooves *b'*, running longitudinally to the body or frame part of the design.

On the upper surface of the body is a socket C, having a central tubular portion *c*, and wings *c'* extending laterally therefrom. Inserted in the socket is the lower end of a rod **20** D, having substantially parallel sides and round in cross-section.

Having thus described my design, what I claim as new, and desire to secure by Letters **25** Patent, is—

The design for a carpet-stretcher, substantially as herein shown and described.

In testimony whereof I affix my signature in presence of two witnesses.

GUY ATHERTON RIGHTER.
